UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed June 24, 1920. Serial No. 391,320.

To all whom it may concern:

Be it known that I, JESSE A. B. SMITH, a citizen of the United States, residing in Stamford, in the county of Fairfield and 5 State of Connecticut, have invented certain new and useful Improvements in Typewriting Machines, of which the following is a specification.

This invention relates to typewriting machines, and is herein disclosed as applied to an Underwood standard typewriting machine.

In such and other machines, the problem frequently confronts the typist of adjusting 10 rapidly and accurately upon the typewriting machine, and relatively to each other, original work-sheets, and work-sheets upon which it is desired to obtain carbon copies of the original, as for example happens in the making 15 of entries simultaneously upon a bill and ledger sheet, by typing upon one and producing a carbon copy upon the other. Many devices have been furnished in these and other machines for aligning such sheets 20 both upon the machines and relatively to each other, but many of said devices were either complex or were not easily adjustable to accommodate the great variety of forms which frequently are used in certain offices. 25 Many, moreover, required the punching of sheets to fit over pins which were used in effecting the aligning.

According to the present invention, there 30 may be provided a comparatively simple 35 device adapted to be readily attached to the typewriting machine, which is adapted to both gage and hold in their gaged positions one or more work-sheets which may be collated or gaged to separate positions upon the 40 machine.

In the form of the invention herein described, there may be provided above the typewriter platen a front gage or aligning plate or paper-table and a series or row of 45 closely spaced devices, arranged along the table in the direction of travel of work-sheets and usable either as sheet-holding clips or as leading-edge gages. These devices are adapted to be normally held clear 50 of the table at ineffective positions, but are adapted to be individually swung to effective position, so that they may lie against the table and serve as end gages or as sheet-holding clips or as both. Also at their ineffective

positions, clear of the table, these devices 55 may serve as side gages. There may be provided a separate set or row of such devices adjacent each lateral edge of the paper-table aforesaid, thus permitting sheets to be separately gaged and detained at either edge 60 of the table, with the result that it is easy for the typist to separately adjust both wide and narrow sheets and to adjust them at any desired relative position upon the table. The 65 clips or gages may be set at one or more line-space intervals apart, thus enabling the rapid alteration of the gaging devices to be effective to suit various work-sheets.

To enable the typist to readily release the gaged sheets, there may be provided for each 70 set of gaging devices or clips a handle universal thereto, which is adapted to be actuated to shift all its devices to ineffective position.

Other features and advantages will hereinafter appear.

In the accompanying drawings,

Figure 1 is a perspective view of an Underwood standard typewriting machine carriage, showing the present invention as applied thereto.

Figure 2 is a perspective view, showing the mounting of a clip.

Figure 3 is a sectional side view of Figure 1, looking to the left.

Figure 4 is a plan view of the clips and their mounting, looking down parallel to the face of the front paper-table.

Figure 5 is a front view of the mounting for the paper-table, showing the mounting of the springs.

In the Underwood standard typewriting machine carriage, a shift or platen frame, comprising a rear paper-table 1 and end plates 2, carries a platen 3 journaled in said end plates and provided with knobs 4 by which it is adapted to be rotated, and also provided with line-space mechanism including a line-space wheel 5.

In the ordinary operation of the machine, a work-sheet 6, with its carbon 7 and record or second work-sheet 8, is adapted to be passed down upon the paper-table 1 and around beneath the platen 3 until it reaches the printing line diagrammatically illustrated by the type-head 9, and when suitably adjusted may be clamped against the platen by feed-rolls 10 and 11, which are adapted

to be actuated by the usual handle 12. When thus clamped against the platen, the work-sheets 6 and 8 and their carbon 7 advance with the rotation of the platen.

According to the present invention, the record sheet 8 and original sheet 6 may be separately gaged and then held in place, before the handle 12 is actuated to throw the feed-rolls 10 and 11 against the platen. For this purpose, there is provided a front paper-table or collating table 13, which is carried upon a cross-bar 14 mounted upon brackets 15, carried upon the end plates 2 and preferably adapted to be detachably attached thereto, as by screws 16 adapted to fit in the usual screw holes for the screws 17, which hold the cover plates 18 upon the end plates 2, thus enabling the paper-table 13 to be readily mounted upon any standard type of Underwood shift frame. The front paper-table 13 is held by screws 19 to lugs or standards 22, which are held in turn by screws 21 to the cross-bar 14.

When it is desired to gage the record or work-sheet 8 upon the paper-table 13, it may be passed up around the platen in the manner described, and slipped up along the face of the table 13 until its leading edge is arrested by the depressed arm 23 of a device 24, which is pressed against the face of the table by its tail 25, against which bears a leaf-spring 26. The arm 23 in bearing against the table 13 serves as a leading-edge gage for the work-sheet 8, which, when thus gaged, may be held in place by pressing down upon it the arm 23 of another device 24 substantially like the first-named device 24, and, like it, journaled upon a rock-shaft 27 carried upon the paper-table 13 and also pressed by another leaf-spring 26, so that when snapped down the second arm 23 serves as a clip and holds the work-sheet 8 in its gaged position. The work-sheet 8 may be also advantageously 45 clipped and detained by a gaging arm 28 of a device 24 at the opposite side of the paper-table 13. The arm 28, which clips and detains the work-sheet 8, may also serve as the leading-edge gage for the second work-sheet 6, which may be separately adjusted to said arm 28 upon the table. The handle or finger-piece 12 may then be actuated to clamp the feed-rolls 10 and 11 against the platen. It is to be noted that the device 24 having the arm 23 forms one of a closely spaced row of such devices arranged along one side edge of the paper-table 13, and that the device 24 having the arm 28 forms one of a similar closely spaced row 60 of these devices arranged along the other side edge of the paper-table 13; the devices in one row co-operative with those in the other row.

To release the gage or clip arms or fingers 23, their shaft 27 may be rocked or ro-

tated by a finger-piece or handle 29 fast thereto, which is adapted to rotate the shaft 27 in its bearings 30 and 31 adjacent the top and bottom of the paper-table 13, respectively. To enable the shaft 27 when thus rotated to restore the devices 24 to their normal positions free of the paper-table 13, there may be provided on the shaft 27 for each device a pin 32 in the form of a screw threaded into the shaft which projects through a restricted slot 33 in the body of its device 24, and is thus adapted, through this lost-motion connection, to turn the devices 24 with the shaft 27 away from their effective sheet-clipping and end-gaging positions to ineffective positions clear of the paper-table 13. When any device 24 is thus turned, its tail 25 slips past dead-center to the dotted-line position of Figure 4, and thus is held clear of the paper-table 13 by its spring 26. For convenience in construction, the springs 26 may be in the form of a comb attached by its body 34 to a cross-bar 35 of a skeleton frame 20. The slots 33 are of sufficient length to allow the arms 23 to be pressed freely against the paper-table 13 by their springs 26, but are short enough to operate the devices 24 in the manner described. Instead of forming a part of the paper-table 13, the journals or bearings 30 and 31 advantageously are formed as extensions or lugs 36 of the skeleton frame 20 which is suitably held to the table 13.

In order to return the handle 29 and to keep it from rattling, it may be normally returned by a spring 37, so that its pins 32 bear lightly against the ends of the slots 33. In their ineffective or non-clipping positions the devices 24 may have their tails 25 normally held in the position shown at the left hand of Figure 1, in which their tails bear against the margin 38 of the paper-table 13, thus permitting their flat faces 39 to be used as a side gage for the work-sheets 6 and 8 at either or both side edges of the paper-table 13, as the case may be, and as is shown in Figures 1 and 4.

It will be noted that if only a single line entry is to be made on each work-sheet, the feed-rolls need not be clamped against the platen, but a single clip device depressed upon each work-sheet will hold it in position during the typing, and the work-sheets may then be readily released by actuating the releasing arms or handles 29 for each set of devices 24 if both sets are used. The devices 24, in the construction shown in the drawings, are adjacent to and in contact with one another and are advantageously made either of a single or a double line-space width or thickness, preferably the former, and are numbered, as indicated in the drawings, to indicate their relative positions. The devices at either side of the table taken collectively co-operate to form a

universal gage for the sheets of paper in the machine, that is to say, a gage whereby the sheets may be gaged for advancing them a predetermined distance of one or more line-space units from any position to which they may have been moved, either as the result of a previous gaging operation or of a previous gaging operation followed by line-spacing of the platen.

10 Variations may be resorted to within the scope of the invention, and portions of the improvements may be used without others.

Having thus described my invention, I claim:

15 1. In a typewriting machine, the combination of a line-spacing platen, a front collating table above the platen at the delivery side thereof and having a side-edge gage, and a universal paper-gage mounted along a side 20 of the table and extending in the direction of the travel of the work-sheets, for facilitating repeated adjustments of the sheets relatively to the machine and to one another, comprising a multiplicity of gaging 25 elements at line-space intervals and movable into positions to grip the work-sheets.

2. In a typewriting machine, the combination with a line-spacing revoluble platen, of a front collating table above the platen 30 at the delivery side thereof, and a universal gage on the collating table for gaging the sheets of a set at intervals to position and reposition them with relation to each other, said gage comprising fingers at line-space 35 intervals, each arranged to serve the dual function of gripping one of the sheets against the collating table and gaging another of the sheets by engagement with its leading edge.

40 3. In a typewriting machine, the combination with a revoluble platen, of a front paper-table or collating table above the platen at the delivery side thereof, rows of closely-spaced devices usable either as sheet-holding clips or as leading-edge gages arranged along the table in the direction of the travel of work-sheets, said devices being 45 individually movable to effective and ineffective positions, whereby a work-sheet may 50 be gaged at its leading edge against one of the effective devices and may be held in such gaged position by another of the effective devices, means for individually holding each of the devices at either its effective or at its

55 ineffective position, rock-shafts upon which said devices are journaled, a connection between each of said shafts and the devices mounted upon it for moving in unison all such effective devices from their effective to 60 their ineffective positions by the rocking of said shaft, and means for rocking the shafts to render all the effective devices ineffective.

65 4. In a typewriting machine, the combination with a revoluble platen, of a front paper-table or collating table above the

platen at the delivery side thereof, a rock-shaft at each side edge of the paper-table, a series of closely spaced devices individually rockable on the rock-shaft to serve either as leading-edge gages for work-sheets or to hold gaged work-sheets in gaged position upon the table, resilient means for individually holding said devices at either effective or ineffective position, and a connection between each device and the corresponding rock-shaft for moving all effective devices from the effective to the ineffective position by the rotation of the rock-shaft.

5. In a typewriting machine, the combination with a revoluble platen, of a front paper-table or collating table above the platen at the delivery side thereof, a rock-shaft at each side edge of the paper-table, a series of closely spaced devices individually rockable on the rock-shaft to serve either as leading-edge gages for work-sheets or to hold gaged work-sheets in gaged position upon the table, resilient means for individually holding said devices at either effective or ineffective position, and a connection between each device and the corresponding rock-shaft for moving all effective devices from the effective to the ineffective position by the rotation of the rock-shaft, said connection comprising a restricted slot 90 provided in each device and a pin projecting from the rock-shaft into said slot so as to have lost-motion therein.

6. In a typewriting machine, the combination with a revoluble platen, of a front collating table above the platen at the delivery side thereof, and rows of paper-clipping devices arranged along the lateral edges of the collating table, the devices at one side of the table being arranged in sheet-gaging relationship to those at the opposite side of the table, the arrangement being such that the lower faces of the clipping devices are positioned along the table at line-space intervals from each other uninterruptedly, from the lowest to the highest thereof, whereby a universal gage is provided for repeatedly positioning the sheets in the machine with relation to each other.

7. In a typewriting machine, the combination with a revoluble platen, of a front paper-table or collating table above the platen at the delivery side thereof, rows of closely spaced devices usable either as sheet-holding clips or as leading-edge gages arranged along the table in the direction of the travel of work-sheets, said devices being individually movable to effective and ineffective positions, whereby a work-sheet 120 may be gaged at its leading edge against one of the effective devices and may be held in such gaged position by another of the effective devices, means for individually holding each of the devices at either its

effective or at its ineffective position, a rock-shaft upon which said devices are journaled, a connection between said shaft and each of said devices for moving in unison all 5 effective devices from their effective to their ineffective positions by the rocking of said shaft, and means for rocking said shaft to render all the effective devices ineffective, said devices being constructed and 10 arranged to form side-edge gages for the work-sheet when said devices are at their ineffective or non-clipping positions.

8. In a typewriting machine, the combination with a platen and a platen frame, of a front paper-table above the platen, a series of devices having faces lying against a margin of the paper-table to form side gages for a work-sheet upon the table, an arm for each device adapted to bear against 15 the table to hold the work-sheet thereupon, and to serve as an end gage for a work-sheet, and a spring for each device adapted to hold it resiliently upon the table.

9. In a typewriting-machine, the combination with a platen and a platen frame, of a front paper-table above the platen, a series of devices having faces lying against a margin of the paper-table to form side gages for a work-sheet upon the table, an arm 20 for each device adapted to bear against the table to hold the work-sheet thereupon, and to serve as an end gage for a work-sheet, a spring for each device adapted to hold it resiliently upon the table, a shaft at the margin of the table upon which the devices are journaled, and connections whereby rotation of the shaft moves all the devices to ineffective position.

10. In a typewriting machine, the combination with a platen and a platen frame, of a paper-table, a plurality of devices adjacent said paper-table adapted to be swung to engage said table, a journal for said devices at the margin of the table, and a comb comprising a spring-arm for each device adapted to hold it resiliently against the table.

11. In a typewriting machine, the combination with a platen and a platen frame, of a paper-table, a plurality of devices adjacent 50 said paper-table adapted to be swung to engage said table, a shaft at the margin of the table forming a journal for said devices, a comb comprising a spring individual to each of said devices to hold them effective, and a 55 finger-piece for rotating the shaft to make the devices ineffective.

12. In a typewriting machine, the combination with a platen and a platen frame, of a paper-table, a plurality of devices adjacent 60 said paper-table adapted to be swung to engage said table, a journal for said devices at the margin of the table, a comb comprising a spring-arm for each device adapted to hold it resiliently against the table, said spring- 65 arms also adapted to hold said devices clear

of the table, and faces on said devices adapted to serve as side gages for a work-sheet lying upon the table.

13. In a typewriting machine, the combination with a platen and a platen frame, of a paper-table, a plurality of devices adjacent said paper-table adapted to be swung to engage said table, a shaft at the margin of the table forming a journal for said devices, a comb comprising a spring-arm individual to each of said devices to hold them effective, a finger-piece for rotating the shaft to make the devices ineffective, said spring-arms also adapted to hold said devices clear of the table, and faces on said devices adapted to serve as side gages for a work-sheet lying upon the table. 75

14. In a typewriting machine, the combination with a platen and a platen frame including a rear paper-table, of a front paper-table, brackets for supporting said front paper-table, a row of clip devices along a margin of said front paper-table, a skeleton frame supported on said brackets and carrying said table, and a comb-plate fast along 80 said frame and comprising individual springs for said devices. 85

15. In a typewriting machine, the combination with a platen and a platen frame including a rear paper-table, of a front paper-table, brackets for supporting said front paper-table, a row of clip devices along a margin of said front paper-table, a skeleton frame supported on said brackets and carrying said table, a comb-plate fast along 90 said frame and comprising individual springs for said devices, a shaft forming a support for said devices, and ears turned up from said skeleton frame forming journals supporting said shaft to permit the shaft to be 95 rotated to move the devices. 100

16. In a typewriting machine, the combination with a revolute platen, of a front collating table above the platen at the delivery side thereof, and universal gages mounted along the lateral edges of the collating table, each gage comprising a multiplicity of gaging elements fixed with relation to the collating table and to each other in the direction in which the work-sheets are fed with 115 their lower gaging faces at line-space intervals along the table, the elements of the two gages being arranged in opposite pairs which have their lower faces lying in the same plane, so that they will be arranged to co-operate in aligning the leading edge of a 120 sheet of paper by simultaneous engagement therewith. 110

17. In a typewriting machine, the combination with a revolute platen, of a front 125 paper-table or collating table above the platen at the delivery side thereof, a series of devices arranged along the table in the direction of the travel of work-sheets and individually movable into one position to 130

form side-edge gages for the work-sheets and into another position for clipping the work-sheets to the table, means for individually holding each of the devices at either of its 5 said positions, a rock-shaft upon which said devices are journaled, a connection between said shaft and each of said devices for moving the devices in unison from their sheet-clipping positions to their positions forming 10 side-edge gages by the rocking of said shaft, and means for rocking said shaft.

18. In a typewriting machine, the combination with a platen and a platen-frame, of a front paper-table on the platen-frame 15 above the platen, a series of devices having faces lying against a margin of the paper-table to form side gages for a work-sheet upon the table, an arm for each device effective to bear against the table to hold the 20 work sheet thereupon and to serve as an end gage for a work-sheet, a spring for each device to hold it in effective position upon the table, and means including a finger-piece for moving in unison all the effective devices to 25 ineffective positions.

19. In a typewriting machine, the combination with a revoluble platen, of a front collating table above the platen at the delivery side thereof, and a series of gripping devices 30 arranged along the table in the direction of the travel of the work-sheets, each being individually movable into position to grip a part of the work and act as a leading-edge gage for another part thereof, said devices

having their gaging portions arranged at 35 equal intervals along the collating table, the extent of such intervals being commensurate with the distance that the platen is advanced by a line-space operation.

20. In a typewriting machine, the combination with a revoluble platen and feed-rollers co-operating therewith, of a front collating table above the platen at the delivery side thereof, and means on the collating table for facilitating repeated adjustments of the 40 work-sheets in the machine with relation to the machine and to each other as the typewriting progresses, said means comprising a series of gripping fingers at each side of the collating table adapted to be moved individually to positions in which they will be effective to grip a part of the sheets and to serve as gages for assisting in separately advancing other sheets predetermined distances 45 from any positions to which they may have 50 been advanced by the line-spacing of the platen and feed-rollers, means for retaining the gripping fingers in effective positions, and means at each side of the collating table 55 for simultaneously withdrawing from effective positions all of the gripping fingers at 60 their respective sides which are in effective positions.
